LINED CONDUIT

Frank H. Janecek, Windham, and Leonard Larson, Shaker Heights, Ohio, assignors to Republic Steel Corporation, Cleveland, Ohio, a corporation of New Jersey

Application November 11, 1943, Serial No. 509,862

2 Claims. (Cl. 138—69)

1

This invention relates generally to the art of protecting walls against abrasive wear and particularly to new and improved means for protecting conduits of blast furnaces against wear by the passage therethru of gases carrying fine abrasive solids.

Blast furnaces are equipped with conduits such as uptakes, bleeders, cross-heads and downcomers thru which highly heated gases carrying small pieces of abrasive solids such as ore, coke and limestone, pass at high velocities. These solids contact with and rapidly wear away the conduits at various places, particularly at elbows and bends, and at other places where gas currents sweep heavily against part of the surface of the conduit. Since the wear caused by the solids is not uniform in all parts of a conduit, certain parts of the conduit walls are worn away more rapidly than other parts and hence part of the conduit becomes useless while other parts could be used for much longer periods of time.

Efforts have been made heretofore to protect the parts of such conduits which are subjected to the greatest wear but, so far as we are informed, none of those efforts has been entirely satisfactory. One proposal to solve this problem was that of making large wear-resistant liner plates, for example, sections as large as four feet by six feet, arranging the plates in edge to edge contact, and securing the margins of the plates to the conduit by bolts, rivets or weld metal. This proposal was unsatisfactory for several reasons. The conduit was subjected to varying temperatures on the outside, while the liner plates were maintained at a high temperature while the blast furnace was operating. The plates buckled and warped due to changing temperatures and often damaged the conduits by bending, springing or actually cracking or breaking the conduit, and sometimes they tore loose from the conduit and slid down along the conduit, often lodging at bends or elbows, thus partly clogging or interfering with the operation of the conduits.

Those and other disadvantages are avoided by the present invention which is predicated on the discovery that liners which are so attached to a conduit as to be able to expand and contract freely and in all directions will not damage the conduit or come loose, and will greatly prolong the life of a conduit. A preferred manner of utilizing the present invention is by using relatively small liner plates, for example 10" square, spacing the edges of each plate a short distance from the edges of adjacent plates and securing

2

each plate in place by suitable attaching means at or near its middle.

In the drawings accompanying and forming a part of the specification,

5 Figure 1 is an elevational view of part of a blast furnace and dust catcher with associated conduits including uptakes, bleeders, cross-heads and downcomers;

Figure 2 is a top plan view of the apparatus 10 of Fig. 1;

Figure 3 is a plan view showing a plurality of liner plates of this invention assembled in a conduit;

Figure 4 is an axial sectional view taken on 15 line 4—4 of Fig. 1 thru the expansion joint thereof; and

Figure 5 is an enlarged sectional view taken on line 5—5 of Fig. 4.

The blast furnace 1 of Figs. 1 and 2 is provided with four uptake conduits 2 more or less equally spaced around the top of the furnace. Two of these uptakes 2 are provided with bleeder conduits 3. Each pair of uptakes 2 are joined by cross-head conduits 4 and each cross-head is 20 connected to a downcomer conduit 5 leading into a dust catcher 6.

It will be understood from Figs. 1 and 2 that gases passing from furnace 1 to dust catcher 6 will pass bends 7 in uptakes 2, will encounter a 30 restriction 8 in bleeder 3, will make sharp turns in direction at 9 when entering crossovers 4, will make other sharp turns and pass thru restrictions 10 in passing into downcomers 5, and will make turns or bends 11 in the latter before entering the dust catcher 6. It will also be understood that in those restrictions and at those turns and bends, much of the fine abrasive material carried by the gases will come forcibly into contact with the surfaces of the conduit and that the resultant 35 abrasive wear caused by the solid particles in the gases will be greater at those points than elsewhere.

The uptakes 2, bleeders 3, cross-overs 4, and downcomers 5 are lined as is indicated in Fig. 1. 45 Preferably the uptakes 2, bleeders 3 and cross-overs 4 are lined thruout, while the upper ends of the downcomers and part of the remainder thereof are lined as indicated. If desired, the entire inner surface of each of these conduits 50 may be lined.

In Fig. 3 a plurality of liner plates 12 are shown connected in assembled relation on the inner surface of a conduit. Each of these plates has its edges 12a spaced a short distance from the edges 55 of adjacent plates. At approximately its center

each plate is attached to the conduit in any suitable manner, for example, as by weld metal 13. It will be understood that the plates need not be square or rectangular, as shown, for they may be of any other suitable shape; and also that they need not be of the dimensions shown which are about 10" x 10" x 1/2", but, on the contrary, may be larger or smaller in length, width and thickness. Preferably, each plate should not be so large that when it expands under operating temperatures it will take up more than about one-half of the space between it and adjacent plates which, as shown, is about 1/8", at normal atmospheric temperatures. If the dimensions of the plates are such that the intervening space between plates can accommodate normal expansion of the plates, the tendency of the plates to press against one another and buckle, warp or apply shearing forces on the securing means will be avoided. The weight of each plate should not be in excess of the strength of the securing means. Furthermore, securing means other than weld metal may be employed but, regardless of the nature of the securing means, the location of the latter should be in the central part of each plate so that expansion of the plate in all directions may take place freely and without imposing any shearing forces on the securing means.

In Figs. 4 and 5 an expansion joint for a lined conduit embodying the present invention is illustrated. In these figures the opposed ends 15 of a downcomer conduit 5 are connected by a seal 16 to prevent the escape of gases. Each conduit end 15 is lined with plates 12 similar to those shown in Fig. 3, and these plates are attached to the conduits by weld metal 13 near their centers. Within the conduit ends 15 a metal ring 17 is attached, as by weld metal 18 at one end thereof, to one of the conduit ends 15, extends past the seal 16 and has a sliding fit with the other conduit end. This ring is preferably equal in thickness to the wear plates 12, so that its inner surface is flush with plates 12 of the conduit ends 15. This ring 17 is provided with a row of wear plates 19 at its ends and with plates 12 between those rows. These plates 19 are similar to plates 12 except that they are somewhat longer, are attached to ring 17 as by weld metal 20, and overlap the plates 12 which are attached to the conduit ends 15 at each end of ring 17. It will be understood from the foregoing description that when the righthand conduit end 15 moves axially relative to the lefthand conduit end to which the ring 17 is attached, the wear plates on the righthand conduit end will slide on the outside of plates 19 attached to ring 17. In this manner the expansion joint is permitted to function while being protected against abrasive wear by the wear plates.

Having thus described the invention so that

others skilled in the art may be able to understand and practice the same, we state that what we desire to secure by Letters Patent is defined in what is claimed.

What is claimed is:

1. An abrasion resistant expansion joint for a blast furnace conduit for gases carrying abrasive solids, comprising opposed metal conduit ends, an exterior gas seal connecting said ends, a metal ring slidably engaging the inner surface of one conduit end and secured to the other conduit end, a plurality of abrasion resisting metal liner plates arranged edge to edge on the inner surfaces of the conduit sections and ring with expansion spaces between the edges of adjacent plates, the plates at the ends of said ring overlapping the plates on the conduit ends, and a single connection between the center part of each plate and the metal conduit.
- 10 2. A conduit for blast furnace gases carrying abrasive solids comprising a rigid, imperforate metal shell and a sectional liner for said shell, said liner consisting of a plurality of thin metal plates arranged with side surfaces against the inner surface of said shell and with expansion spaces between edges of adjacent plates, and weld metal extending thru and filling holes provided therefor in said plates at their central points, said weld metal constituting the sole means for supporting and connecting the plates to the shell.
